United States Patent Office.

F. SHELLY, OF ALTON, ILLINOIS.

Letters Patent No. 99,012, dated January 18, 1870.

IMPROVEMENT IN LIME-KILNS.

The Schedule referred to in these Letters Patent and making part of the same.

To all whom it may concern:

Be it known that I, F. SHELLY, of the city of Alton, county of Madison, and State of Illinois, have invented a new and useful Improvement in Lime-Kilns, of which the following is a full, clear, and exact description, reference being had to the annexed drawings, making a part of this specification, in which—

Figure 1 represents a sectional elevation of my invention, taken at $z z$ of fig. 3.

Figure 2 represents a sectional elevation of same, taken at $y y$ of fig. 3.

Figure 3 represents a plan of same, at the line $z z$ of figs. 1 and 2.

Similar letters indicate like parts.

The object of my invention is to economize space and material in constructing, and fuel and labor in operating lime-kilns, and I accomplish it by uniting several cupolas or kilns in one stack, and by other details hereinafter set forth.

A, in the several figures, represents a stack, built of brick, rectangular in form, and sufficiently large to be divided internally, by two transverse partitions, B, C, at right angles to each other, into four cupolas, D, which number, experience tells me, is most advantageous, though, of course, this may be increased, if desired, by simply adding other partitions, and increasing the size of the stack.

The wall B is made somewhat thicker and higher than C, though both are considerably lower than the top of the stack.

Both stack and dividing-walls may be lined with fire-brick in the usual manner.

G, in the several figures, represents the furnaces, of which there are two to each compartment, extending into the stack, one on either side of the compartment, to the back of same, and there connecting with it by lateral passages K.

The entrances of the furnaces are lined with fire-brick or clay frames H, let into the walls, flush with

the surface of the same, and the peep-holes I are also lined with fire-clay.

By means of passages L, leading from the front of the furnaces, the cupolas are supplied with fresh air for mixture with the gases beyond the fire-bed.

Now, in order to dispose of the increased production of a kiln of this kind, without a corresponding increase of manual labor, which is a needed improvement in those kilns now in use which unite several cupolas in one stack, I arrange the delivery-chutes E, at the bottom of the cupolas, in a recess, as seen in fig. 1, the chutes being extended, however, beyond the wall of the stack, at a sufficient height to allow a wagon beneath it, to receive its deposits, while that portion of the continuation of the chute within the recess is provided with a screening-grate, E', so that the screenings may fall into a receptacle placed in the recess to receive them, so that one and the same operation discharges the cupolas, screens the charge, and loads the wagons with the pure and clean lime; thus saving materially the amount of labor required.

Suitable doors are provided above the chute, to regulate the drawing of the charges; and to protect the brick-work, the chutes are lined with boiler-iron.

I, of course, do not claim, generally, the arrangement of two or more cupolas in one stack, since kilns now in use possess this feature; but

What I do claim as my invention, and desire to secure by Letters Patent, is—

The combination, with the cupolas D, of discharge-chutes E and screening-grates E', arranged in recesses in the side of the stack A, and constructed and operating substantially as and for the purpose shown and specified.

F. SHELLY.
